UNITED STATES PATENT OFFICE.

ALEXIS LEBEDEFF, OF PETROGRAD, RUSSIA.

SILENCER FOR INTERNAL-COMBUSTION ENGINES.

1,217,021.

Specification of Letters Patent. Patented Feb. 20, 1917.

Application filed February 15, 1916. Serial No. 78,474.

To all whom it may concern:

Be it known that I, ALEXIS LEBEDEFF, a subject of the Emperor of Russia, residing at Wassili Ostrow, 11 line, house No. 3, 5 Petrograd, Russia, have invented certain new and useful Improvements in Silencers for Internal-Combustion Engines; and I do hereby declare the following to be a full, 10 clear, and exact description of the invention, such as will enable others skilled in the art to which it appertains to make and use the same, reference being had to the accompanying drawings, and to letters and figures of reference marked thereon, which 15 form a part of this specification.

The hitherto proposed silencers or apparatuses designed to suppress the noise produced by the exhaust gases of internal combustion motors do this work, as is well-known, 20 only in a very unsatisfactory manner; nevertheless they absorb a considerable per cent. of the power of the motor. To attain a good result with a minimum of power absorbed by the silencer, the same must produce a rapid cooling of the hot gases and 25 as little as possible embarrass the output of them.

Now the object of this invention is a new 30 type of silencers for internal combustion motors generally and especially for those used on flying machines of any kind and motor vehicles, which silencer, being very simple in construction, does nevertheless its work with good result and, when used on 35 aeroplanes or other bodies or structures, which are moved at a great velocity, does not diminish the power of the motor in an appreciable manner.

Figure 1 of the drawings shows an embodiment of my new silencer partly in a 40 longitudinal section and partly in a side view, whereas Fig. 2 is a front end view of same and Fig. 3 a cross section on line A—B of Fig. 1.

The new silencer comprises an outer shell 1 of thin metal sheet, eccentrically fixed on the end of the exhaust tube 7 of the motor, an inner conical tube 2 tightly connected at its larger end to the rear end of the said shell 1, and a large cylindrical pipe 5 tightly fixed to the front end of the same shell and the rear end 4 of which is progressively diminished in diameter to such an extent that 50 between the same and the narrower front end of the conical tube 2 is left a slot 3, through which the annular chamber 6,

formed by the said shell 1, and tubes 2 and 4, 5—communicates with the cone 2. 8 and 9 designates metal strips by which the pipe 4, 5 and the cone 2 respectively are connected or suspended to the outer shell 1 with a view to increase the inner rigidity of the apparatus.

The outer shell 1 has preferably the form of a cigar or grenade or generally of a body 65 which gives the smallest possible resistance upon the air.

As appears from Figs. 1 and 2, the exhaust gases are by the pipe 7 introduced into the free annular space 6 of the silencer 70 in such a direction that the hot gases are induced to move along this space in a spiral travel.

When the flying machine or, generally speaking, the body supporting a silencer of 75 the described kind is moved in the direction indicated by the arrow "x," the air flow produced thereby around the shell 1 and within the pipe 5 and cone 2 in the direction of the arrow "y" will, firstly, energetically cool the 80 metallic walls and thereby also the gases circulating within the space 6 and, secondly, draw these latter through the circular slot 3 into the cone 2 and out of this latter. Experience has shown that a silencer of this 85 kind, duly dimensioned for a given motor, works at a distinct velocity of motion of the apparatus in the direction of the arrow x without absorbing any appreciable amount of power from the motor, and with a very 90 good result as far as the suppressing of noise is concerned.

What I claim is:

1. A silencer for internal combustion engines, comprising an outer metallic shell, a 95 large inner pipe tightly connected to the front end of the said shell and having a successively contracted rear end, a truncated cone tightly fixed at its large end to the rear end of the said shell and encircling with its 100 narrower front end the rear end of the said pipe so as to form a circular slot, and means for eccentrically introducing into the free annular space formed by the said shell, pipe and cone, the hot exhaust gases, substantially as described and illustrated by drawings.

2. A silencer for internal combustion engines, comprising an outer metallic shell, a 110 large inner pipe tightly connected to the front end of the said shell and having a successively contracted rear end, a truncated

cone tightly fixed at its large end to the rear end of the said shell and encircling with its narrower front end the rear end of the said pipe so as to form a circular slot, and means for eccentrically introducing into the free annular space formed by the said shell, pipe and cone, the hot exhaust gases.

3. A silencer for internal combustion engines, comprising an outer metallic shell having tapered ends, a large inner pipe tightly connected to the front end of the said shell and having a successively contracted rear end, a truncated cone tightly fixed at its large end to the rear end of the said shell and encircling with its narrower front end the rear end of the said pipe so as to form a circular slot, and means for eccentrically introducing into the free annular space formed by the said shell, pipe and cone, the hot exhaust gases.

4. A silencer for internal combustion en-

gines comprising an outer metallic shell eccentrically mounted upon the end of a tube feeding the hot exhaust gases, a large inner pipe tightly connected to the front end of the said shell and having a successively contracted rear end, a truncated cone tightly fixed at its large end to the rear end of the said shell and encircling with its narrower front end the rear end of the said pipe so as to form a circular slot, and means for eccentrically introducing into the free annular space formed by the said shell, pipe and cone, the hot exhaust gases.

In testimony that I claim the foregoing as my invention, I have signed my name in presence of two subscribing witnesses.

ALEXIS LEBEDEFF.
